UNITED STATES PATENT OFFICE.

THOMAS WHITE SMITH, OF LONDON, ENGLAND.

DESIGN FOR BANNER-BORDER COMBINATION-TYPE.

Specification forming part of Design No. 7,805, dated October 20, 1874; application filed September 7, 1874.
 [Term of Patent 3½ years.]

To all whom it may concern:

Be it known that I, THOMAS WHITE SMITH, of the firm of H. W. CASLON & Co., at 22 Chiswell street, in the city of London, England, have invented a Design for Banner-Border Combination-Type, of which the following is a specification:

My design is fully represented by the accompanying illustration, to which reference is made.

Figure 1 represents the various parts of the combination-type with brass rule; and Fig. 2, a banner-border produced from that type.

a, b, c, d, e, f, g, h, and i are parts of the border. *j* are brass rules. The body *z* of the banner may be supplied with letters or figures, or other representations, as may be desired.

In place of using black ink, various effects may be obtained by printing in colors.

What I claim as my invention is—

The design for banner-border combination-type, herein shown and described.

THOS. WHITE SMITH.
